UNITED STATES PATENT OFFICE.

CHARLES A. FOX, OF NEW YORK, N. Y.

COLLAPSIBLE BOX.

Application filed April 29, 1927. Serial No. 187,431.

This invention relates to improvements in receptacles and has particular reference to a collapsible box.

An object of the invention is to provide

- 5 an improved box of simple and practical construction, the side and end walls of which may be readily and quickly adjusted from collapsed to set-up position and securely retained in the latter position.
- 10 Another object is to provide one of the walls of the box with a flap which, by a lateral movement in the direction of and relative to the other wall, may be forced into engagement with and held by a locking
- 15 means on said other wall so that the flap will support the walls in set-up position.

The above and other objects will appear more clearly from the following detail description, when taken in connection with the 20 accompanying drawings, which illustrate preferred embodiments of the inventive idea.

In the drawings—

Figure 1 is a perspective view of a box 25 constructed in accordance with one form of the invention;

Figure 2 is an enlarged fragmentary end elevation;

Figure 3 is a section on the line 3—3 of 30 Figure 2;

Figure 4 is a fragmentary plan view of the box shown in Figure 1 with the side and end walls collapsed;

Figure 5 is a fragmentary plan view of 35 the blank from which the box is formed;

Figure 6 is a fragmentary perspective view of the interior of one corner of the box constructed in accordance with another form of the invention;

40 Figure 7 is a horizontal sectional view through said corner; and

Figure 8 is a fragmentary plan view, partly broken away showing the corner of Figure 6 is collapsed position.

45 The construction involved herein is particularly adapted for use in connection with comparatively shallow boxes wherein the walls are approximately two and three inches in height, but it will of course be understood that said construction may be applied to other types of boxes without departing from the spirit or scope of the invention. The drawings illustrate only the bottom or body of the box, it being understood that 50 the top or cover thereof may be of the same

construction as the body or of any other desired form. The box, as is customary with receptacles of this type, is made of fibre board.

Referring more particularly to Figures 1 to 5, the box is shown as comprising a bottom 10 and side and end walls 11 and 12 which are defined by the fold lines 13 and 14, respectively. The sheet or blank of material from which the box is formed is 60 cut to provide a tapered corner flap 15 at each end of each side wall. Each flap is bent around the adjacent end of an end wall and said flap is permanently secured, adjacent the corner of the box, to said end wall 65 by means of suitable fasteners 16 in the form of staples or the like, this fastening operation being known in the art as stitching. It will, of course, be understood that the permanent attachment of the flap to the end 70 wall may be accomplished by any other suitable means, such as an adhesive or the like.

At each end of each end wall the material is scored diagonally from the lower corner of the end wall to provide a folding line 75 80 which permits of the adjacent side wall being collapsed inwardly, as shown in Figure 4, upon the bottom of the box with the corner flap extending in the same plane with said side wall and outwardly beyond said 85 folding line. When in this position the box is completely collapsed and a great many of them may be stacked in this position and with the utilization of a minimum amount of space.

Adjacent each end of each of the end walls the material is cut to provide a transverse slot 18, the ends of which terminate short of the upper and lower edges of the wall, and said slot is disposed at a distance 90 from the end of said wall which will permit the free extremity of the corner flap 15 to overlap said slot. At each end of the slot the material is further cut in the direction of the opposite end of the end wall to provide 95 the longitudinal slots 19 to thereby form a locking tongue 20 which may be flexed inwardly and outwardly relative to the remainder of the wall. The material at the ends of the slot 18 is further cut in the opposite direction from the slots 19 on diverging lines 21 to form a yielding portion 22 opposed to the locking tongue 20 and the cuts 21 are at such angles that the distance 100 between the cuts will be slightly greater 105 110

than the width of the portion of the flap 15 adjacent said cuts for a purpose which will presently appear.

When it is desired to adjust the side and end walls of the box to their operative or set-up position it is only necessary for the operator to simultaneously grasp said side walls adjacent one end of the box and pull upwardly thereon, whereupon said side walls 16 will move about the folding lines 17 and in so doing will draw the adjacent end wall to an upstanding position. As this operation is being performed the thumb of each hand may be engaged with the adjacent corner flap 15 and by pressing inwardly on said flaps in the direction of the end wall the free extremity of each flap will be engaged with the overlapped locking tongue 20 and also with the yielding portion 22. Further pressure applied to said extremity will force both the tongue and portion 22 inwardly, the angle of the cuts 21 affording sufficient space for the edges of the flap to pass inwardly without actually contacting the edges of the material of the end wall forming said cuts. The pressure is applied until the free extremity of the flap passes from the outer side of the locking tongue to a position on the inner side thereof, whereupon said extremity will have virtually been forced into the slot 18. After this has been done the locking tongue 20, owing to the flexibility of the material, restores to its normal position with the extremity of the flap interposed between said tongue and the yielding portion 22, as shown in Figure 3. In this position the portion 22, which has a tendency to restore to its normal position in a plane with the remainder of the end wall, exerts an outward pressure upon the free extremity of the flap 15 and will thus operate to bind the same against the locking tongue 20 with the result that said flap will be retained in its locked position against any ordinary outward pressure and the walls of the box will thereby be braced in position. It is to be noted also that when the flap 15 is locked the same overlaps the folding line 17 and thus avoids bending of the material along said line while the flap is locked. After the corner flaps have been thus locked in position at one end of the box the operation just described is repeated at the other end thereof.

In the form of the box illustrated in Figures 6 to 8, the blank thereof is cut in precisely the same manner as shown in Figure 5, but instead of securing each corner flap to the outside of the end wall, as in the first form described, said flap is secured to the inner side of said end wall, as clearly illustrated in Figure 6. In this construction the diagonal folding lines 17 are scored so that the end walls will first fold inwardly upon the bottom of the box and then the side

walls will collapse inwardly as shown in Figure 8. In this case also the flaps 15 will fold inwardly and assume a position between the end and side walls instead of being extended outwardly, as illustrated in Figure 4. With the corner flaps disposed inwardly of the end walls it will of course be understood that when the same are to be engaged with the locking tongue 20 the pressure applied to the free extremities of said flaps is in an outward direction instead of inwardly as previously described.

In accordance with the present invention it will be understood that instead of forming the corner flaps 15 as extensions of the side walls, said flaps may be formed on the ends of the end walls and bent around the side walls, in which event the latter walls will be formed with the slats 18, 19 and 21 and the flaps 15 will be locked in the same manner as previously described.

What is claimed is:

1. In a collapsible box of the type wherein the side and end walls collapse against the bottom, a bottom, side and end walls one of which is provided with a corner flap extensible along the other wall when the box is in set-up position, means to permanently secure said corner flap to said other wall, and said other wall having means actuated, after said side and end walls have been disposed in substantially perpendicular position relative to said bottom, by engagement of the free extremity of said flap therewith and a lateral pressure against said flap in the direction of said other wall to lock said extremity thereto.

2. In a collapsible box of the type wherein the side and end walls collapse against the bottom, a bottom, side and end walls one of which is provided with a folding line and the other with a corner flap extensible along the first named wall in overlapping relation to said folding line to brace the latter wall when the box is in set-up position, means to permanently secure said corner flap to said first named wall, and the latter wall having means actuated, after said side and end walls have been disposed in substantially perpendicular position relative to said bottom, by engagement of the free extremity of said flap therewith and a lateral pressure against said flap in the direction of said first named wall to lock said extremity thereto.

3. In a collapsible box of the type wherein side and end walls collapse against the bottom, a bottom, side and end walls one of which is provided with a corner flap extensible along one surface of the other wall, means to permanently secure said corner flap to said other wall, the latter wall being formed with adjacent yielding portions both of which are overlapped by the free extremity of said flap when the box is in set-up

position, and one of said portions forming a locking tongue movable laterally, after the side and end walls have been disposed in substantially perpendicular position relative to said bottom, by a pressure on the flap in a direction toward said other wall to permit said extremity to pass beyond said tongue and into engagement with the opposite surface of said other wall.

10 4. In a collapsible box of the type wherein side and end walls collapse against the bottom, a bottom, side and end walls one of which is provided with a corner flap extensible along one surface of the other wall,

15 means to permanently secure said corner flap to said other wall, the latter wall being formed with adjacent yielding portions both of which are overlapped by the free extremity of said flap when the box is in

20 set-up position, one of said portions forming a locking tongue movable laterally, after the side and end walls have been disposed in substantially perpendicular position relative to said bottom, by a pressure on the

25 flap in a direction toward said other wall to permit said extremity to pass beyond said tongue and into engagement with the opposite surface of said other wall, and the other yielding portion being also initially movable laterally by said pressure and thereafter exerting an outward pressure upon said flap

to bind the same against said locking tongue.

5. In a collapsible box of the type wherein the side and end walls collapse against the bottom, a bottom, side and end walls one of which is provided with a corner flap extensible along the other wall when the box is in set-up position, means to permanently secure said corner flap to said other wall, the latter wall having a transverse slot and other slots extending in opposite directions from the ends of said transverse slot to form adjacent yielding portions overlapped by said flap when said box is in set-up position, one of said yielding portions forming a locking tongue movable laterally, after the side and end walls have been disposed in substantially perpendicular position relative to said bottom, by a pressure on the flap in a direction toward said other wall to permit said extremity to pass beyond said tongue and into engagement with the opposite surface of said other wall, and the other yielding portion being also initially movable laterally by said pressure and thereafter exerting an outward pressure upon said flap to bind the same against said locking tongue.

In testimony whereof I have affixed my signature.

CHARLES A. FOX.
